US00D590129S

(12) **United States Design Patent**
Warman

(10) **Patent No.:** **US D590,129 S**
(b4) **Date of Patent:** **** Apr. 14, 2009**

(54) **UNDERPANTS**

(76) Inventor: **Ben Jay Warman**, 3 Brookfield,
Gosforth, Newcastle-upon-Tyne, NE3
4YB (GB)

(**) Term: **14 Years**

(21) Appl. No.: **29/240,658**

(22) Filed: **Oct. 17, 2005**

(30) **Foreign Application Priority Data**

Apr. 16, 2005 (GB) 3020943
May 4, 2005 (GB) 3021122
